L. FRASCH

DOOR HOOK

Filed July 17, 1924

FIG. 2.

Inventor
Louis Frasch.

By *Clarence A. O'Brien*
Attorney

UNITED STATES PATENT OFFICE.

LOUIS FRASCH, OF TWO RIVERS, WISCONSIN.

DOOR HOOK.

Application filed July 17, 1924. Serial No. 726,575.

To all whom it may concern:

Be it known that I, LOUIS FRASCH, a citizen of the United States, residing at Two Rivers, in the county of Manitowoc and 5 State of Wisconsin, have invented certain new and useful Improvements in Door Hooks, of which the following is a specification.

This invention relates to door hook structures especially adapted to be used for securing swinging doors, and it consists in the novel features hereinafter described and claimed.

The hook structure may also be conveniently used in conjunction with either swinging or sliding doors, and the structure includes a yoke member adapted to be mounted upon a support adjacent the door, there being a bumper mounted upon the yoke 15 member and a spring actuated hook pivotally mounted thereon. A catch member is adapted to be applied to the door and may engage the bumper and the hook simultaneously.

20 In the accompanying drawing:

Figure 1 is a side elevation of the door hook.

Figure 2 is a top plan view thereof.

The door hook structure comprises a yoke 25 member 1, which may be secured to a suitable support 1', adjacent a swinging or sliding door. A cushion 2 is mounted upon one end portion of the yoke member 1 and may serve as a bumper for the door. A hook 3 is pivoted at a point between its ends to the yoke member 1 as at 4, and the point 5 of the hook is disposed opposite one end of the yoke member 1 and above the cushion or bumper 2. A pull rod 7 is pivotally connected at its upper end with the hook 3, and the lower portion of said pull rod passes transversely through the intermediate portion of the yoke member 1. A nut 8 is screwed upon the lower end of the pull rod 40 45 and holds a treadle 6 on the pull rod. A coil spring 9 is interposed between the

upper end of the pull rod 7 and the inner surface of the intermediate portion of the yoke member 1, and the convolutions of the spring 9 are coiled around the intermediate portion of the pull rod 7. The spring 9 is under tension with a normal tendency to hold the pointed end 5 of the hook 3 in a lowered position. A catch member 10 is adapted to be applied to the door. The catch member 10 is provided with an angularly disposed end portion 11 adapted to engage under the point 5 of the hook, when the door moves toward the hook structure. When the catch member 10 is in engagement with the pointed end portion 5 of the hook 3, as shown in Figure 1, and it is desired to release the door from the hook structure, the treadle 6 is depressed, whereby the hook 3 is swung upon the pivot 4, and the pointed end 5 of the hook is carried above the angularly disposed end portion 11 of the catch 10 and the door to which the said catch is applied may be moved with relation to the hook structure.

Having described the invention, what is claimed is:

A door hook structure comprising a yoke member including an intermediate portion and a pair of side portions, said intermediate portion adapted to be attached to a support, a hook pivoted intermediate its ends to the end of one side portion and having an end portion located within the yoke member, a cushioning bumper mounted upon the end of the other side portion, a pull rod slidable through the last mentioned side portion and pivotally engaged with said end of the hook, a spring on said pull rod for holding said end of the hook toward the side on which said hook is pivoted, and a catch member adapted to be engaged by the cushioning bumper and provided with an angularly disposed end portion adapted to be engaged by the hook.

In testimony whereof I affix my signature.

LOUIS FRASCH.
